(57) **CLAIM**

The ornamental design for an emergency flotation device, as shown and described.

DESCRIPTION

FIG. 1 is a top plan view of an emergency flotation device; FIG. 2 is a left side view thereof; the right side view being an identical mirror image thereof;

FIG. 3 is an elevation view thereof;

FIG. 4 is a bottom plan view thereof; and,

FIG. 5 is a side isometric view thereof.

The broken lines illustrate portions of the emergency flotation device and form no part of the claimed design.
